COIN CONTROL

Sam May, Chicago, Ill., assignor of one-half to
Raymond T. Moloney, Chicago, Ill.

Application June 5, 1944, Serial No. 538,773

12 Claims. (Cl. 194—9)

1

This invention pertains to a coin control for use with various types of coin-operated vending and amusement machines.

It is a principal object of the invention to provide a simple control unit and cooperating circuit means and instrumentalities which make it possible to dispense with a number of relays and associated wiring and electrical instrumentalities in machines of the class described, particularly relays and switches for counting coins deposited, whereby to simplify such machines and effect economies in material and manufacturing costs therefor.

A further object is the provision of a coin control adapted to handle any number of coins for separate control circuits, and to effect certain movements of all such coins through the agency of only one principal moving member and one actuating means therefor.

Another and more particular object is the provision of a control unit of the class described including a coin shuttling device, switch means actuated by coins moved into certain positions by such device, and a single electromagnet actuating means and circuit connections for actuating the shuttling device.

A still more specific object of the invention is the provision of a coin control including a stationary bed in which a shuttle reciprocates for the purpose of moving a coin from a receiving position into an intermediate switch-controlling position at which the coin blocks a switch-operating finger, whereby to set up certain control circuits, the switch-operating finger being moved by the shuttle to enable the coin to pass into and out of its various positions, together with electrical circuit and shuttle actuating means associated with the control.

Further objects, advantages, and aspects of novelty attaching to the invention relate to certain details of construction and operation of the device hereinabove characterized, all of which will appear more fully as the following description proceeds in view of the annexed drawings, in which:

Fig. 1 is a perspective view of the novel control unit in association with certain vending machine instrumentalities;

Fig. 2 is a vertical section through the control device, alone;

Fig. 3 is another vertical section through the control device with the shuttle in advanced position;

Fig. 4 is a circuit diagram for a vending or coin-controlled apparatus employing the novel control means;

2

Fig. 5 is a top plan view of a modified form of the control which embodies a switch-control feeler operated by the shuttle;

Fig. 6 is a sectional view looking in the direction of lines 6—6 of Fig. 5;

Fig. 7 is a sectional view looking in the direction of lines 7—7 of Fig. 5;

Fig. 8 is a sectional view looking in the direction of lines 8—8 of Fig. 7;

Fig. 9 is a sectional view similar to Fig. 8 but with the shuttle in advanced position and raising the switch-operating finger;

Fig. 10 is a perspective detail of modifications in the coin blocks for cooperation with the feeler type of control shown in Figs. 5 through 9.

Coin handling devices are known in the art in which coins are moved by slides for divers purposes, including the operation of switches, the novelty of the present invention residing more particularly in the especial form and mode of operation of the control unit, notably the shuttling means, and in certain circuit connections and instrumentalities associated therewith.

In Fig. 1 there is shown the coin handling mechanism for a vending machine utilizing the present invention, said mechanism including a vertical support 10, upon which are mounted a number of coin testing devices or chutes 11 and 12 of known construction and operation. Only two such testing devices are shown, but it should be borne in mind that any number may be employed. In an upper shelf section 13 of the support there are provided openings 14 and 14' through which coins are deposited into the testing chutes.

After passage through one of the chutes in the well known manner, a coin, if acceptable, will be discharged into the opening 15 or 15' of a corresponding receiving block 16 or 16' mounted on a movable part or shuttle 18 of the coin control unit.

The coin control unit includes a relatively stationary member or bed 17 secured, as by brackets 17' to the main support just below the coin chutes. Mounted to slide for reciprocation in the bed portion 17 is a movable member or shuttle 18 having a coin passage 19 for each coin handling section therein corresponding to one of the chutes 11 or 12, this passage 19 not being apparent in Fig. 1, but being visible in Fig. 2.

Blocks 16 and 16' are each secured to the top of the shuttle in alignment with a corresponding one of the openings 19, it being understood that the novel coin control may be adapted to handle any number of coins from individual testing

chutes, and that there will be a set of coin handling shuttling passages, each with its own coin receiving block 16, etc., constituting what is termed for convenience a "coin handling section" in the control unit, there being as many such sections as there are coin testing chutes 11 or 12.

Spring means 21, anchored at one end 22 to the bed 17 and at the other end 23 to the shuttle (this means being duplicated at the opposite side of the control unit, not seen) urges the shuttle into a starting or normal position with the blocks 16 and 16' disposed beneath their respective coin chutes.

Means such as an electromagnetic solenoid 24, having a plunger 24a connected with the shuttle, is provided for effecting withdrawal of the shuttle from normal to advanced position, the normal position being shown in Fig. 2, also, and the advanced position being shown in Fig. 3. It is contemplated that means other than the solenoid 24 may be used for advancing the shuttle, for example, manually actuated lever means.

The internal construction of the control unit is best understood from examination of Fig. 2, wherein it is seen that the movable part or shuttle 18 is of somewhat U-shape, consisting of an end portion 18a from which extend overlying upper and lower shelf sections 18b and 18c.

A stationary shelf section 16a, forming part of the bed, projects in between the overlying movable shelves or arms of the shuttle, and it will be observed in Fig. 2 particularly that there is a coin passage 16b in the stationary shelf, and that there are also coin passages 18X and 18Y in the overlying shelf portions of the shuttle, and that in the normal position of the shuttle, all of these coin passages 16b, 18X, and 18Y are in register, passage 18X being mainly a sight-opening, however, and useful in some installations for observation of the coin on the control switch.

It will be observed further in Fig. 2 that the coin receiving or deposit passage 19 of the shuttle is normally disposed over the stationary shelf section of the bed, so that a coin C received from the corresponding coin chute would lie in the position shown on this stationary shelf 16a, so long as the shuttle remained in normal position.

As seen in Fig. 2, the shuttle includes a coin rest 18Z disposed (when the shuttle is advanced as in Fig. 3) to underlie the coin passage 16b in the stationary shelf so as to hold a coin C¹ while the shuttle remains in advanced condition. The underside of the movable or shuttle coin rest is cut away, as at 26 (Fig. 2), to accommodate the operating arm 27 of a control switch 28 mounted on the underside of the bed, and the switch operating arm 27 extends upwardly through an opening 29 in the bed so as to be engaged by the coin C¹, for example, when the latter drops as a result of removal of the coin rest section 18Z upon return to normal position.

A coin exit 16X is provided in the bed for register with the shuttle passages 18X and 18Y when the shuttle is advanced, so that the coin C¹, upon a subsequent reciprocation of the shuttle, will fall therethrough in the manner of the coin shown in dotted lines in Fig. 3 and designated C³.

The travel of a coin through the control unit is described as follows: assuming a coin to be received from one of the chutes into the passage 15 of block 16, such coin will drop at once onto the stationary shelf section 16a, as represented by the coin C in Fig. 2, and the coin will remain

in this position until the shuttle is moved from normal position, as by solenoid 24; and upon advance of the shuttle, as in Fig. 3, the coin C¹ will move toward the left with the shuttle and drop through passage 16b onto the coin rest 18Z of the lower shelf section of the shuttle, where it will remain as long as the shuttle stays in advanced condition; but upon de-energization of the solenoid, spring means 21 will restore the shuttle to the position of Fig. 2, and coin C¹ will at once drop through passage 18Y onto the switch operating arm 27, to depress the latter and actuate switch 28 for purposes hereinafter described. A coin shown in dotted lines, and designated C² illustrates this condition in Fig. 2.

A coin will occupy the position of coin C² until the next operation of the shuttle, whereupon it will be pushed toward the left into passage 16X in the bed for final discharge therethrough as illustrated by the coin C³ of Fig. 3.

It will thus appear that it requires three movements of the shuttle from normal position to effect discharge of a coin after it is received in the unit.

25 A control circuit and instrumentalities cooperating with the new coin control device in a vending machine, are illustrated in the diagram of Fig. 4, wherein there are associated with each coin chute or testing device 11 or 12, a master coin switch 30 or 30' respectively. Since the control circuits for any number of coin handling sections in the unit are identical, only one such circuit, that associated with chute 11, is described in detail.

35 Master coin switch 30 is connected to energize coil 31 of a holding relay from ground 32, via said switch 30 closed, (as by a coin in passing from chute 11) conductors 33, battery or other power source 34, ground 35.

40 Such energization of coil 31 attracts the relay armature 36 against contacts 37 and 45 to apply a locking or holding ground for this relay via contact 37, armature 36, vending solenoid breaker switch 39, which is normally closed, and ground 40.

45 A vending solenoid coil 41 has one terminal connected through coin control unit contacts 28 (when closed), conductor 44, relay contact 45 closed with armature contact 36, to ground via normally closed breaker contacts 39, and the other terminal of this coil connects with normally open contact 50 of a vending switch.

50 As soon as an acceptable coin passes through chute 11 into block 16 of the control unit, switch 30 closes momentarily, thus energizing the holding relay, which locks its own holding circuit at contacts 36-37. Also, an operating circuit for the vending solenoid 41 is set up through relay contacts 36-45, conductor 44 to the coin control unit switch 28, which, however, at this time will be open because there will be no coin on the operating arm 27 until the shuttle is operated (excepting in the instances mentioned herein-after).

55 In order to cause the deposited coin to be lodged upon switch operating arm 27, it is necessary that the shuttle be operated, and operation of the holding relay as just described sets up circuit connection for this purpose through the ground from armature contact 36, contact 45, conductor 44a, normally closed vending switch contacts 49, 53, to the coil 24X of the shuttle solenoid, which will be energized from battery 54, grounded at 52, by reason of which the shut-

tie is advanced the moment the holding relay pulls up.

This advance of the shuttle will dislodge any coin previously on the coin switch operating arm 27, and the coin which is assumed to have been deposited in the operation now described will remain on the shuttle sustaining-shelf portion 18Z (Fig. 3) until the shuttle is released for return to normal position; as soon as this happens, switch 28 will be closed and vending solenoid 41 may then be energized by the patron's pushing vending button 48 to close contacts 49-50. Such operation of the vending button also opens contacts 49-53 to de-energize coil 24X and release the shuttle, thus causing the deposited coin to drop on arm 27 and close switch 28, which results in the actuation of the vending means shown schematically at 47 and designated "Vend I," it being understood that such vending means may be any of the well known vending mechanisms, or actuating devices therefor, operation of which, as aforesaid, will cause some desired article of merchandise, such as candy bars, cigarette packs or a phonograph selection, etc., to be delivered.

Upon energization of the vending solenoid as aforesaid, the plunger 46 thereof engages and opens breaker switch 39, thus interrupting the holding ground 40 to armature contact 36 of the holding relay, breaking its holding circuit, so that it becomes necessary to deposit another coin in chute 11 before the aforesaid cycle of operations can be repeated.

It will be seen that the foregoing actuation of the shuttle under control of the patron will cause the controlling coin thereby delivered onto the control switch operating arm 27 to remain on the latter after the vending operation and release of the holding relay; therefore, if it is assumed that the patron now deposits another coin in the same chute 11, the operating circuit for the vending solenoid and shuttle solenoid will nevertheless not be conditioned for operation until the newly deposited coin actuates the master coin switch 30 to energize the holding relay. When this happens, the application of ground from 36-45-44a causes the advance of the shuttle as before, and the previously deposited coin which was resting on the switch operating arm 27 is dislodged therefrom and discharged from the control unit in the manner already explained, and the second deposited coin is moved onto the switch operating arm 27 when the patron pushes the vending button, as before.

Two coin handling sections or vending circuits have been illustrated in Fig. 4, prime numbers designating parts corresponding to identical parts in the circuit just described.

Thus, had the coin in the foregoing example been deposited in chute 12, instead of chute 11, holding relay coil 31' would have pulled up its armature to lock its own holding circuit at contacts 36'-37', and the shuttle would have been advanced by reason of operating ground from 40', relay contacts 36'-45', conductor 44a', vending switch contacts 49-53, and as soon as the vending switch were operated to open contacts 49-53, allowing the shuttle to return to normal and cause deposit of this coin to close coin control switch 28', the vending solenoid 41' would be conditioned for operation by closure of contacts 49-53, and operation of this vending solenoid would result in delivery of the merchandise associated with coin chute unit 12 (vend II), opening breaker switch 39' to drop out the holding relay, as in the first example.

It will be observed that when the patron deposits a coin in any one of the several coin testing devices, a corresponding holding relay at once pulls up and locks, and the shuttle device advances and remains advanced until the vending switch is operated. By this time the patron may have deposited a second coin in another chute, but this second coin will nevertheless be received in the corresponding coin handling section of the control unit because the receiving blocks 16, 16' are arranged to receive coins from the chutes in either normal or advanced position, the only difference being that when the shuttle is in normal position, the first coin to be deposited would lodge on the stationary shelf section 16 (coin C) as in Fig. 2, whereas if the second, or any number of subsequent coins, be deposited after the shuttle has advanced, then such coins would fall through passage 16b and lodge directly upon the movable shelf or sustaining section 18Z, as in Fig. 3.

In either case, return of the shuttle to normal position will cause all of said coins to drop onto the corresponding switch operating arms 27, 27', etc., such arms being cleared of previously deposited coins by the initial advance of the shuttle.

Shuttle-controlled switch-operating means

A further feature of the novel control is illustrated in the construction of Fig. 7, wherein the basic construction of the shuttle means is substantially the same as heretofore described, there being a bed member 60, in which reciprocates a shuttle 61 urged into normal position by spring means 62. A top shuttle arm 63 is provided with a coin receiving passage 64 having therebelow a stationary shelf 65 upon which the received coin first lodges.

When the shuttle advances to the position of Fig. 9, the received coin is pushed by movement of the top arm 63 into a passage 66 in the stationary ledge 65, where it rests upon the then underlying lower shuttle arm section 67. When the shuttle returns to normal position, the passage 68 in the lower shuttle arm will be moved beneath the passage 66 to occupy the place theretofore occupied by the sustaining portion 67, so that the coin will drop onto the bed 60 as illustrated in Fig. 7.

Coin-controlled switch operating means includes a switch-operating finger 70 pivotally mounted on bracket means 71 secured to the bed portion 60. This finger includes a nose portion 72 adapted to project downwardly into the aligned passages 64A (the latter being a sight-opening also, in the top shuttle arm) 66, and 68, when the shuttle is in normal position, so as to engage and depress the extension 73 of switch arm 74 and separate the latter from its companion contact 75 when there is no coin on the bed above the switch.

Spring means 76 anchored at one end to upright pin 77 on the bed, and at its remaining end to a crank arm extension 78 of finger or feeler 70, urges the latter clockwise into the position of Fig. 7 to engage the coin, if any, or the switch extension 73 if no coin be present.

The switch-operating finger or feeler 70 is provided with an angled offset 79 which is engaged by the adjacent edge of the shuttle when the latter advances, whereby the feeler is pivoted upwardly into the position of Fig. 9 to withdraw its nose from the coin passages, so that the coin may be shuttled freely from one position to the next.

In Fig. 8, the two conditions of operation of the

feeler and switch means are illustrated. At the left of this figure the coin 80 is shown blocking the nose portion 12 from engagement with the switch operating extension 73, while at the right, in the adjoining coin-handling section, there is no 5 coin, and hence the nose 12 engages and depresses the switch extension 73 and opens the corresponding switch blades for control purposes hereinafter referred to, Fig. 6 showing said switch in open condition.

In the aforesaid modified form of the control as illustrated in Figs. 5 through 10, identical solenoid means to that indicated at 24, 24a in Figs. 1 and 2, is employed to effect reciprocation of the shuttle, cooperatively with spring means 62. Such actuating means is indicated schematically in Fig. 9, wherein a solenoid coil 90 is shown with its plunger 91 connected with a stud 92 on the shuttle.

Summary of operation

Assuming that a patron deposits a coin in both chutes 11 and 12, such coins will, if acceptable, transiently engage and operate the coin switches 30 and 30' and pass into their respective receiving openings 15, 15' (Fig. 1) in blocks 16, 16', at once dropping onto the stationary shelf sections 16a (Fig. 2) in their respective sections.

Operation of the two switches 30, 30' (Fig. 4) causes both holding relay solenoids 31, 31' to be energized, and both relays lock their own holding circuits through their respective contacts 36-37, and 36'-37'. Also, ground from 40 and 40' is applied through the corresponding breaker switches 39, 39' and relay contacts 36-45, 35 36'-45' to vending switch contact 49 via conductors 44a, 44a', so that the shuttle solenoid 24X is at once energized from battery 51, grounded at 52, causing the shuttle to move to advanced position (Fig. 3).

The two deposited coins will initially occupy a position like that of the coin C in Fig. 2, and when the shuttle advances, such coins will drop, as through a passage such as 16b in Fig. 3, onto the movable or shuttle shelf portion 18Z in their 45 respective sections of the shuttle.

Operation of the two holding relays having set up operating circuits for their respective vending solenoids 41, 41', through their corresponding coin control unit switches 28, 28', the patron may now push delivery plunger 48, which will open shuttle holding contacts 49-53, thus causing the shuttle to be restored to normal position, whereupon the coins occupying the position of a coin C¹ of Fig. 3, will drop onto the switch operating arms 27, 27' in their respective sections, closing corresponding switches 28, 28', and thus energizing the two vending solenoids 41, 41', whereby to actuate the associated vending apparatus 47, 47' designated "Vend I," "Vend II."

As a result of the aforesaid actuation of the vending solenoids, their respective plungers 48, 48' will open corresponding breaker switches 39, 39', thus breaking the holding grounds 40, 40' for the two holding relays, whereby the machine is restored to starting condition. The fact that coins may or may not remain on switch operating arms 27, 27' makes no difference, as will appear from the fact that all previously deposited coins are cleared by the initial advance of the shuttle.

The novel coin control unit may be associated with any number of coin chute devices, 11, 12, etc. and any number of corresponding vending mechanisms 41-47, 41'-47', etc., and only one actu-

ating device 24X and vending delivery control 48-49-50-53 will be required regardless of the number of coin handling sections in the unit, whereby the patron may make one selection and cause one article to be delivered at a time, or he may make any number of various selections at one time and cause delivery of all selected articles at once. The control device eliminates separate coin counting relays, which are usually stepping switches of relatively costly construction, compared with the costs involved with the simple control unit herein described, and in addition, only one moving part, the shuttle 18, and one actuating means 24X (or 90) is needed to effect controlling movements of any number of coins in various coin-handling sections in a given shuttle.

In some coin-operated machines, it is desirable that the coin last deposited, that is the one last to operate the machine, be disposed in view in order that spurious coins or slugs may be seen, should they pass the testing chutes, and to this end the coin control provides a sight-opening 18X (or 64A) through which such coins may be viewed, as for example, the coin C² of Fig. 2.

By appropriate dimensioning of the thickness of the shuttle and bed sections 16a, 18b, and 18c, the control unit shown in Figs. 1 to 3, especially, may be adapted to operate with more than one coin at a time; for example, the tension of control switch spring blades 27-28 may be selected to require the weight of two or more coins at one time, instead of one, in order that switch means 28 may be closed. For installations of this type, the embodiment of Figs. 1 through 3, employing the weight-actuated switch is preferred. On the other hand, some types of coin machine may be intended to be operated by tokens, instead of coins, and such tokens may be of insufficient weight to depress the control switch blades 27-28 positively, and in such cases the feeler-operated switch means of Figs. 5 through 9 is desirable.

It will be observed that in the construction of Figs. 5 through 9, coin-receiving or collecting means such as the blocks 16, 16', are omitted, since this modified unit is intended to operate with a coin chute or testing device capable of dropping the accepted coin into a position in which it will fall into the passage 64 of the shuttle in either normal or advanced position.

However, in those installations where the receiving block structure 16 is used with the type of control unit shown in Fig. 7, for example, which includes the feeler 18, the construction illustrated in Fig. 10 is employed, wherein the coin-receiving blocks 96 and 96' are mounted on the upper or top shuttle arm portion 63', and each such block is provided with a vertical slot 96X or 96Y aligned with the corresponding feeler finger 70X or 70Y, 60 such that when the block moves forward with the shuttle, the corresponding feeler fingers will be received within said slots and be freely movable therein.

It is to be understood that the form of control unit shown in Figs. 5 through 9 may be substituted in the circuit arrangement of Fig. 4 without any other changes, the difference being that whereas the switches 28 are normally biased into open-circuit condition, to be closed by the weight 65 of the coins to be deposited thereon, as described, the switch means of Fig. 7, for example, is normally biased into closed-circuit condition, but is held in open-circuit condition so long as there is no coin thereabove, the nose of the feeler depressing the operating extension 73 for this pur-

pose; but when a coin is present, as in Fig. 7, then the nose of the feeler is blocked and rendered ineffective to open the corresponding switch.

The novel control unit is intended for use with any form of coin-operated machine, the operation of which may be caused by devices such as the solenoids 41, 41' (or any analogous electrical instrumentality); and the delivery means 49—53 need not be manually actuated, but if desired may be actuated in conjunction with other instrumentalities commonly associated with various types of coin-operated machine; and since alterations may be desirable in adapting the novel control means to these various types of coin-operated machine, the invention is not intended to be limited or confined to the exact structural and functional details herein set forth for illustrative purposes, excepting as may be specifically provided for in the appended claims.

Having thus described my invention, what I claim as new and desire to protect by Letters Patent of the United States is:

1. Coin control apparatus comprising in combination, a plurality of vending solenoids, a breaker switch actuated by each vending solenoid in operated condition, a holding relay associated with each vending solenoid, a delivery switch, a master coin switch associated with each holding relay to energize the latter at least momentarily by action of a coin closing a corresponding said master switch, each holding relay having contacts closing a locking circuit therefor upon energization of a said relay by a master switch as aforesaid, a bed, a shuttle reciprocable in said bed, means yieldingly urging said shuttle into a normal position in said bed, a shuttle solenoid for advancing said shuttle from normal to advanced position in the bed, separate series of correlated coin passages and coin sustaining parts in said bed and shuttle, there being one such series corresponding to each of said master coin switches, a coin control switch associated with a certain passage in each said series of passages and each connected with holding relay contacts and said delivery switch in such manner that operation of the latter switch, when the corresponding holding relay is energized and the corresponding coin control switch is operated by a coin, will effect actuation of the corresponding vending solenoid, the corresponding vending breaker switch aforesaid being connected to deenergize the corresponding holding relay upon actuation of the vending solenoid, contact means on all holding relays for energizing said shuttle solenoid when any said relay is energized, said coin passages and sustaining parts in each section being arranged and constructed to receive a coin which has actuated any master coin switch as aforesaid and transport said coin into operative engagement with the corresponding coin control switch responsive to one complete reciprocation of the shuttle, and to discharge said coin from operative relation with the corresponding control switch responsive to an advance of the shuttle from normal position, said delivery switch being connected to deenergize said shuttle solenoid upon operation of said switch in actuating a vending solenoid as aforesaid.

2. Coin control apparatus comprising a stationary member, a shuttle reciprocable in said member, coin passages and sustaining parts in said member and shuttle and cooperable in certain positions of the shuttle whereby a coin is moved progressively into successive positions by certain reciprocatory motions of the shuttle, a control switch at one said position operated by a coin

transported thereto as aforesaid, one of said passages constituting a receiving opening, a master coin switch adjacent said receiving opening and actuated by a coin in moving into said opening, 5 a holding relay energized by operation of said master switch, a locking circuit for said holding relay and closed by the same upon energization as aforesaid, an electrically actuated vending device, circuit connections for operating said vending device and set up by said holding relay upon energization as aforesaid, and further energized by said control switch upon actuation of the latter by a coin, electrical means for moving said shuttle in one direction and energized by said 10 holding relay energized, switch means for deenergizing said electrical moving means and breaking the actuating circuit for said vending device, circuit breaker means for releasing said locking circuit upon each operation of the vending device 15 as aforesaid, and means yieldably urging said shuttle into a normal starting position.

3. A coin control comprising a bed, a shuttle reciprocable in said bed, means yieldably urging said shuttle into a normal position, means operable to withdraw said shuttle from normal to an advanced position, a coin receiving passage in said shuttle, a coin sustaining ledge on the bed to sustain a coin in said receiving passage when the shuttle is in normal position, a coin passage in said 20 bed and displaced from said receiving passage in the direction of advance movement of the shuttle away from normal position, a control device operated by a coin and situated beneath said passage in the bed, a coin sustaining part on the shuttle 25 disposed above said control device and beneath the aforesaid passages when the shuttle is advanced from normal position, a coin exit passage in said shuttle offset in advancing direction from the first-mentioned passage therein, a coin exit 30 passage in said bed registering with said exit passage in the shuttle when the latter is in said advanced position, whereby a coin deposited in said receiving passage with the shuttle in normal or advanced position will be deposited in operative engagement with said control device consequent upon movement of the shuttle from normal to advanced position and back to normal position, and said coin in engagement with the control device will thereafter be dislodged through said exit 35 passages upon a subsequent advance of the shuttle from normal position.

4. A coin control unit comprising a bed, a shuttle reciprocable on said bed, spring means urging said shuttle into a normal position, electromagnetic means for advancing said shuttle from normal to advanced position, a plurality of coin receiving blocks on said shuttle and each corresponding to a separate coin handling section of the unit, coin passages in said bed and shuttle 40 and adapted to register in certain normal and advanced positions of the shuttle, there being a separate series of said passages corresponding to each said section, coin sustaining parts in the bed and shuttle in each said section to sustain a coin with respect to certain of said passages in certain advanced and normal conditions of the shuttle, a coin actuated device associated with a certain coin passage in each said section, said blocks being adapted to receive a coin in either normal or advanced condition of the shuttle, all aforesaid being constructed and arranged so that a coin deposited in any of said blocks in either normal or advanced position of the shuttle will be transported into operative engagement with the corresponding control device responsive to

one complete reciprocation of the shuttle, and will be moved out of operative engagement with the control device responsive to an advance of the shuttle from normal position following reciprocation as set forth.

5. A coin control comprising a shuttle including upper and lower shelves spaced apart vertically, a bed mounting said shuttle for reciprocation and including a bottom and a shelf spaced apart vertically with said shelf disposed between said shelves in the shuttle, a coin passage in the upper shelf of the shuttle, a first coin passage in said bed shelf and displaced from said passage in the shuttle shelf in the direction of movement of the shuttle from a normal position in which said stationary bed shelf is substantially fully disposed in between the upper and lower shelves of the shuttle, a second coin passage in the lower shelf of the shuttle offset from the first passage therein, a coin actuated control member disposed for operation by a coin in said second shuttle passage when the shuttle is in normal position, a coin sustaining portion on said lower shuttle shelf to sustain a coin in said first bed passage when the shuttle is in advanced position, whereby a coin deposited in said passage in the upper shuttle shelf, with the shuttle in normal position, will rest on said bed shelf, said coin moving onto said sustaining portion on the lower shuttle shelf upon movement of the shuttle to advanced position, said coin dropping into operative engagement with said control device upon return of the shuttle to normal position, said coin being moved out of operative engagement as aforesaid by the next subsequent advance of the shuttle.

6. Coin control apparatus for an electrical delivery circuit, comprising a bed, a shuttle reciprocable in said bed, coin-actuated means for reciprocating said shuttle, coin passages in said bed and shuttle arranged to effect passage of a coin deposited in a certain one of said passages by a succession of movements of said shuttle to an intermediate position, thence to discharge said coin, a control switch at said intermediate position, and delivery-effecting electrical means in circuit with said switch such that the presence of a coin at said intermediate position is required to render said switch effective for actuation of said delivery-effecting means.

7. A coin control including a reciprocable shuttle comprising a pair of tiered parallel plates interleaving with a bed having tiered, spaced levels, said plates and levels all provided with cooperative coin passages including a receiving passage, an exit passage, and an intermediate coin station arranged such that a reciprocation of said shuttle from a normal position will effect transit of a coin from said receiving passage to a position of rest at said intermediate station, switch means including an actuating extension at said intermediate station for control cooperation with a coin thereat, said switch means being adapted for connection in a delivery control circuit rendered operable dependently upon the presence or absence of a coin at said intermediate station, said coin being removed from said intermediate station to said exit passage by a subsequent movement of the shuttle following the aforesaid reciprocation thereof.

8. A coin control including a reciprocable shuttle and bed therefor, both provided with cooperative coin passages including a receiving passage, an exit passage, and an intermediate

coin station, arranged such that a plurality of reciprocations of said shuttle from a normal position will effect transit of a coin from said receiving passage to said intermediate station, at which the coin is permitted to rest after a first reciprocation, and thence to said exit by a second reciprocal movement of the shuttle, switch means including an actuating extension disposed at said station for control cooperation with a coin thereat, a feeler normally engaging said extension to operate said switch means, a coin at said station blocking said feeler and preventing operation of the switch means as aforesaid, said switch means being adapted for connection in a delivery-control circuit rendered operable dependently upon the presence or absence of a coin at said intermediate station.

9. Control apparatus as defined in claim 8 and further characterized in that said feeler is mounted to be moved by said shuttle away from said intermediate station to permit movement of a coin by the shuttle relative to said station.

10. A control device comprising a bed, a shuttle reciprocable in said bed, said bed and shuttle having cooperative coin passages adapted to effect transit of a coin from a receiving position to an intermediate station responsive to movement of the shuttle, a coin-receiving block movable with said shuttle and adapted to receive coins in a plurality of positions of the shuttle for delivery into a certain one of said passages, a control extension at said intermediate station, a movable feeler normally and yieldably urged into engagement with said control extension to operate the same and adapted to engage a coin at said station in a manner to prevent operative engagement with said extension, said feeler being moved by said shuttle, in certain motions of the latter, away from said station to permit movements of a coin relative to the station, said coin block having a slot formation in which said feeler may move as aforesaid responsive to movements of the shuttle.

11. Coin control means including a stationary member and a reciprocable member movable back and forth relative to the stationary member, both said members having adjacent coin-sustaining and coin-passage portions disposed in the line of reciprocation of the reciprocable member and placed to effect movement of a coin deposited in a passage portion into a control station on a stationary sustaining portion responsive to one complete reciprocation of the reciprocable member, and to effect discharge of said coin from said station responsive to a movement of the reciprocable member subsequent to complete reciprocation thereof as aforesaid, and switch means operably controlled by presence and absence of a coin at said station, said last-mentioned means adapted to control operation of an associated instrumentality, said switch means having an operating element disposed at said station, and a yieldably urged switch-actuating member normally disposed to engage said operating element when there is no coin at said station and actuate said switch in predetermined manner, and blocked from actuating the switch means by a coin at said station.

12. In a coin control, a pair of stationary plates spaced apart one above another, a shuttle including a pair of similarly spaced plates jointly movable in interfitting relation with said stationary plates, the uppermost shuttle plate overlying the uppermost stationary plate, said shuttle

adapted to reciprocate relative the stationary plates, a coin entrance in the uppermost shuttle plate, a coin exit in the lowermost stationary plate and offset in line of reciprocation from said entrance, a coin passage in the lowermost shuttle plate and offset similarly from said entrance passage, a coin operated control member underlying said passage in the lowermost shuttle plate when the latter is inwardly disposed in the stationary plates, said passages related spatially such that one complete reciprocation of the shuttle following deposit of a coin in said entrance passage will lodge said coin in operative engagement with said control member, said coin being dislodged therefrom into register with said

15

exit passage by a subsequent outward movement of the shuttle.
